CLAIM

The ornamental design for an implant tray and a retainer cap of a nerve stimulator package, as shown and described.

DESCRIPTION

FIG. 1 is an isometric, exploded view of an implant tray and a retainer cap of a nerve stimulator package; FIG. 2 is an isometric view of the implant tray of the nerve stimulator package;

FIG. 3 is a front side view thereof.

FIG. 4 is a back side view thereof.

FIG. 5 is a right side view thereof.

FIG. 6 is a left side view thereof.

FIG. 7 is a top side view thereof.

FIG. 8 is a bottom side view thereof.

FIG. 9 is an isometric view of the retainer cap of the nerve stimulator package;

FIG. 10 is a front side view thereof.

FIG. 11 is a back side view thereof.

FIG. 12 is a right side view thereof.

FIG. 13 is a left side view thereof.

FIG. 14 is a top side view thereof; and,

FIG. 15 is a bottom side view thereof.

In FIG. 1 the broken lines disclose the environment of the claimed design and form no part of the claimed design.
